UNITED STATES PATENT OFFICE.

ROBERT WARG, OF MILWAUKEE, WISCONSIN.

STEAM-TRAP.

No. 889,648.

Specification of Letters Patent.

Patented June 2, 1908.

Application filed July 15, 1907. Serial No. 383,724.

To all whom it may concern:

Be it known that I, ROBERT WARG, a citizen of the United States, and resident of Milwaukee, in the county of Milwaukee and 5 State of Wisconsin, have invented certain new and useful Improvements in Steam-Traps; and I do hereby declare that the following is a full, clear, and exact description thereof.

10 The object of my invention is to provide a simple, durable and efficient steam-trap for radiators, steam-coils, heating-systems or the like, said invention consisting in certain 15 peculiarities of construction and combination of parts as hereinafter fully set forth with reference to the accompanying drawing and subsequently claimed.

The accompanying drawing shows a longitudinal section view of a steam-trap embodying the features of my invention, with parts broken away and in section to more clearly illustrate the details.

20 Referring by letter to the drawing, A indicates a cylindrical casing and B a detachable head therefor, the casing being provided with a steam-inlet opening C and an outlet 25 D, which outlet communicates with a hollow foot portion E of said casing.

The bottom wall of the casing is provided 30 with a tappet-opening a, which communicates with the foot E, said opening being adapted to receive the threaded end of a nipple F, into which nipple is tightly fitted a sleeve G as shown. This sleeve is preferably 35 composed of hard copper, the upper edge of which forms a valve-seat, while the lower edge thereof abuts a shoulder b of the nipple. Seated upon the sleeve and forming a closure 40 therefor is a solid tobin bronze plunger H, which plunger together with the hard copper sleeve comprises the trap discharge-valve. The plunger is provided with suitable guides 45 c, c, formed in a hood I, the lower open-end of the hood being threaded for the reception of a corresponding threaded shank of the nipple F, by which said hood is supported.

Condensation from the trap-casing is discharged through a series of openings d in the hood I, the said hood being also formed with 50 an ear e to which is pivoted a slotted lever J, that is connected to the upper end of the plunger by means of a pin f, as shown. To one end of this lever is secured a stem g of a copper globe-float K, which is arranged to 55 open the valve when the condensation has

accumulated to a predetermined height in the casing.

As shown in the drawing the valve is in its closed position with the float K resting just above the lower wall or bottom of the casing, 60 there being a well L formed in said bottom to permit clearance of the float, said well also serving as a cavity to receive any accumulation of mud or sediment.

The upper wall of the casing is provided 65 with a dome M to permit rise of the float when acted upon by the condensation, said dome being tapped for a vent-cock N, while the well L has a capped opening N' therein for blow-off purposes, and a depending support h as shown. The float is limited in its upward movement by a bridge-piece i of the lever, which bridge-piece is adapted to engage the ear e of the hood.

In order to positively open the valve, the 75 casing-head carries a threaded stem O, which projects in the path of the bridge-piece i, and may be run in to engage the latter and thus lift the plunger from the seat, there being a hand-wheel j at the outer end of the stem for 80 actuating the same.

From the foregoing description it will readily be understood that when the water-line in the casing has risen to a sufficient height, the float will cause the valve to open, 85 and thereby permit the condensation to flow freely through the hood and thence to the outlet, until such time as the float has dropped to its normal or closed position, caused through the discharge of said con- 90 densation.

The particular advantage of the construction of discharge-valve described, is that the constant hammer of the hard metal plug upon the soft-metal valve-seat tends to 95 smooth off said seat and in a measure retain a perfect fit between the parts so as to prevent leak of the valve. Should the seating of the parts however become imperfect through long wear or other causes, the same 100 may readily be repaired, access being had to the valve by removing the head. This repair is accomplished by removing the hood and facing off the sleeve with a file or other abrasive. The yoke and plunger may then 105 be disconnected and said plunger also refaced, after which a dressing of emery and oil may be applied to its face. The hood can now be readjusted to the nipple and the plunger dropped into place therein, and by 110

- revolving the same upon the sleeve or seat with a slight pressure the grinding motion will cause the contacting faces to become perfectly seated with relation to each other. Thereafter the emery-paste is removed and the yoke being connected to the hood the mechanism is again intact. The above operation can be resorted to from time to time as required without incurring the necessary delay and expense in replacing the parts, which heretofore has been the practice where valves of ordinary construction are used. As the valve-seat is gradually worn down through regrinding, it will cause a corresponding gradual sag of the float, which owing to the well formed in the ring, will not contact with the bottom thereof, the bridge-piece forming a stop as the float rises to prevent the same from striking the wall of the closure, as said valve is opened.
- The sleeve G is preferably cut from a metallic tube section of standard consistency and molded or otherwise secured into the nipple, this construction being desirable for the reason that it is practically impossible to cast the same in one piece with the nipple and retain a uniform density of metal in all nipples.
- I claim:
1. A float-valve comprising a nipple, a

sleeve fitted therein, an apertured hood in threaded connection with the nipple, guides in the hood, a reciprocative plunger fitted in the guides and adapted to seat upon the sleeve, an ear projecting from said hood, a slotted lever pivoted to the ear, means connecting the plunger and lever, and a bridge-piece carried by the lever arranged to abut said ear.

2. A steam-trap comprising a closed casing having inlet and outlet openings, a nipple secured to the outlet opening having a valve-seat therein, a hood in connection with the nipple, a plunger valve-closure carried by the hood, an ear projecting from the hood, a float-lever pivoted to the ear, a bridge-piece extending from the lever arranged to abut said ear, an adjustable spindle in threaded engagement with the casing alined with the bridge-piece, and means connecting the float-lever and plunger valve.

In testimony that I claim the foregoing I have hereunto set my hand at Milwaukee in the county of Milwaukee and State of Wisconsin in the presence of two witnesses.

ROBERT WARG.
